UNITED STATES PATENT OFFICE.

DANE SPEHAR, OF MIAMI, ARIZONA.

DRILLING-MACHINE.

1,244,385.

Specification of Letters Patent. Patented Oct. 23, 1917.

Application filed January 25, 1917. Serial No. 144,414.

To all whom it may concern:

Be it known that I, DANE SPEHAR, a citizen of the United States, and a resident of Miami, in the county of Gila and State of 5 Arizona, have made certain new and useful Improvements in Drilling-Machines, of which the following is a specification.

One of the principal objects of my invention is to provide an improved drilling machine 10 designed particularly for prospecting work which may be operated by one man, and so constructed that it may be readily taken apart, and packed in a relatively small space for transportation.

15 Another object of the invention is to provide an improved drilling machine which is mechanically operated, and in which the blows are delivered through the alternate contraction and expansion of a spring.

20 A further object of the invention provides an improved method of automatically causing the intermittent rotation of the drill.

A still further object of the invention is 25 to provide an improved drill which is comparatively simple, durable, efficient in operation, and inexpensive to manufacture and maintain.

With these and other objects in view which will become apparent as the description 30 proceeds, the invention resides in the construction, combination and arrangement of parts hereinafter more fully described and claimed, and illustrated in the accompanying drawings in which like characters of reference indicate like parts throughout the several figures, of which:

Figure 1 represents an elevational view of a drill constructed according to my invention.

40 Fig. 2 represents an elevational view looking at right angles to Fig. 1.

Fig. 3 represents an elevational view of a portion of the drill shaft showing the arrangement of the key-ways.

45 Fig. 4 represents a longitudinal sectional view taken through the drill on the plane indicated by the line 4—4 of Fig. 1.

Fig. 5 represents a horizontal sectional view taken on the line 5—5 of Fig. 4.

50 Fig. 6 represents a horizontal sectional view taken on the line 6—6 of Fig. 4.

Fig. 7 represents a horizontal sectional view taken on the plane indicated by the line 7—7 of Fig. 4.

55 Fig. 8 represents a view in perspective of the trigger.

Fig. 9 represents a horizontal sectional view taken on the plane indicated by the line 9—9 of Fig. 4.

Fig. 10 represents a fragmentary vertical 60 sectional view taken on the plane indicated by the line 10—10 of Fig. 6.

Fig. 11 represents a fragmentary elevational view of the ratchet sleeve and the trigger associated therewith, showing the 65 position of the parts as the sleeve begins an up-stroke.

Fig. 12 represents a similar view showing the position of the parts during the up-stroke of the sleeve, and

70 Fig. 13 represents a similar view showing the position of the parts during the down-stroke of the sleeve.

Referring more particularly to the drawing, a cylindrical casing, in which the drill 75 shaft reciprocates, is indicated at 5, and at the lower end of the casing is disposed a plug 6, through which the drill shaft or spindle slides, said plug being threaded into the end of the casing and being provided with a polygonal head 7, whereby it may be readily removed when desired.

The upper end of the casing is turned into an internally threaded boss 8, which carries the spaced legs 9 of a handle. The 85 boss may be secured against rotation relatively to the casing by means of set screws 10. The upper ends of the legs 9 are offset outwardly from each other and support a suitable handle 11, whereby the operator 90 may grip the machine. A spreader 12 is arranged between the lugs 9 for suitably spacing and supporting them.

Extending laterally from the legs 9 are the opposite pairs of spaced ears 13 and 14 95 respectively, such ears forming terminals of strips of metal secured by rivets or other suitable fastenings 15 to the opposed inner faces of the legs 9. Threaded into an opening in each ear is a brass or other suitable 100 bushing 15, and these bushings support the stub shafts 16. Each pair of ears thus rotatably supports one of the shafts 16. Mounted on the shafts 16 for rotating them are the intermeshing gear wheels 17 of similar size, and from this arrangement it follows that when one of the gears is driven the shafts 16 will be driven in opposite directions, and at a common rate of speed. Adjustably mounted by a bolt and slot connection indicated at 18 on one of the gears 17, 110 is a crank arm 19, carrying a crank handle

20, by means of which the gears may be manually driven.

Keyed on each of the shafts 16, between the bosses in which such shaft is journaled, is a driving gear. Each driving gear includes a pair of spaced substantially annular plates 21, which plates at diametrically opposed points, are flattened as at 22 (see Fig. 4.) Connecting these plates adjacent their peripheries are the opposed series of pins 23 and 24, on which pins and between the plates, rollers 25 are mounted.

The rollers are situated at equally spaced apart points, around the entire periphery of the plates 21, except at those portions of the plates which are flattened, as indicated in Fig. 4 and this construction forms in effect interrupted or mutilated driving gears. These gears move in opposed directions, and 20 at a common rate of speed as the gears 17 are rotated.

The upper portion of the spindle or shaft is indicated at 26 and the lower portion of said shaft at 27. Segment 26 is provided 25 on opposed sides with substantially cylindrical rack teeth 28 having flattened lower surfaces 29, and the rack teeth in each series correspond in number to the number of rollers 25 in each of the two series of rollers 30 carried by the driving gears. The teeth 28 project inwardly beyond the peripheries of the driving gears, said segment 26 being, as indicated in Fig. 4, arranged between the driving gears, and as indicated in the drawing, as the driving gears are revolved, the rollers 25 engage beneath the teeth 28 and move the drill spindle upwardly until such time as opposed flattened portions 22 of the driving gears move into proximity with the segment 26, at which time the teeth 28 will be free of engagement with any of the rollers, whereby the spindle is released, it being moved downwardly under the influence of the spring 30 for delivering a blow. By 45 having each of the driving gears equipped with two series of rollers 25, it will be evident that the spindle will be raised twice during one complete revolution of the gears 17, so that rapid blows will thus be struck, 50 without driving the gears 17 above a moderate speed.

While the upper segment 26 of the spindle has a reciprocatory motion only, the lower segment 27 has a rotary as well as a reciprocatory motion, and in order to allow rotation of the lower segment relatively to the upper, a suitable coupling is provided. This coupling includes a split shouldered ring indicated generally at 31, and each of the segments of the ring has formed thereon an upwardly extending arm 32 provided with a lug fitting into an indentation 33 formed in the spindle segment 26. Suitable set screws 34 detachably secure each of the arms 32 to 60 the spindle segment 26. The shoulders

formed on the ring segments 31 thus form a collar which fits into a groove 35 cut in the upper end of the spindle segment 27 and circumferentially of the same. In disconnecting the spindle segments, it is only necessary to unscrew the set screws 34 sufficiently to disengage the segment 26 whereupon the segments of the spindle may be taken apart. 70

A spring 30 before mentioned bears at its upper end against an annular ring 36 arranged within the casing 5, and held against movement upwardly, in said casing, by means of a collar 37 riveted or otherwise secured in place as indicated at 38. The lower end of the spring bears against a ring 39 which is loose within the casing, and which abuts against the upper end of the ratchet sleeve 40. This sleeve is keyed or otherwise fixed on the spindle segment 27, and moves with said segment. When the spindle is 85 drawn upwardly as the gears are rotated, the spring is compressed, and at the moment that the spindle is released the action of the spring in forcing the spring downwardly, delivers a working blow. Downward movement of the spindle, if not previously stopped by engagement of the drill point with the work, is limited by the movement of the lower end of ratchet sleeve 40 into engagement with the plug 6. 95

Arranged within the casing is a ratchet wheel 41. This ratchet wheel surrounds the ratchet sleeve and said ratchet sleeve is adapted to reciprocate through the wheel. This wheel is held against reciprocatory movement relatively to the casing by means of a substantially U-shaped keeper indicated at 42, the ends of which keeper projecting toward the spindle occur above and below the ratchet wheel. The keeper does not, however, interfere in the slightest with the rotary movement of the ratchet wheel. In order that the ratchet wheel and ratchet sleeve will rotate in unison at the same time that the sleeve reciprocates relatively to the wheel, said wheel is provided with gib keys 43 slidable in grooves in the sleeve, hereinafter described. 105

In order that the ratchet wheel 41 will be allowed to rotate only in one direction, 115 spring pressed pawls 44 are provided. These pawls are arranged at diametrically opposed points of the ratchet wheel, and are connected by means of bolts or other fastenings 45 with lugs 46 formed on the 120 casing 5 of the machine.

The ratchet sleeve 40 is provided exteriorly with a plurality (preferably 12) of longitudinally extending equally spaced grooves or key-ways 47, having squared upper and lower ends 48, and the grooves 47 are interconnected adjacent their upper ends by inclined ways 48a which extend in a common direction and which occur at an angle of about 60 degrees, as clearly shown in 130

Figs. 11 to 13 inclusive of the drawing. Adapted to ride in the grooves 47 are a pair of diametrically opposed triggers indicated generally at 49. These triggers are arranged within the cylindrical casing 5, and each includes a cylindrical portion 50 mounted for oscillation at one end in a socketed plug 51 (see Fig. 10) threaded into an opening in the wall of casing 5. The triggers each include a substantially rectangular shoe 51^a adapted to ride in the grooves or keyways, and at right angles to its shoe 51^a each key is equipped with a weighted arm 52 thrust downwardly by a spring 53 carried by the casing 5 (Fig. 6).

The shoe portions 51^a of the triggers fit for sliding movement into one of the grooves 47 on opposite sides of the ratchet sleeve 41, and as the sleeve moves downwardly with the spindle as the working stroke is imparted through the action of the expanding spring 30, each shoe will, so to speak, ride upwardly in a groove in which it fits until the end of the working stroke is reached, at which time the shoe will be at the upper end of the particular groove in which it may happen to be working. As the shoe comes opposite the upper end of the inclined way 48^a leading into this groove, the action of the spring 53 in continuously pressing downwardly on the arm 52, will move the shoe 51^a into alignment with the said inclined way in the position indicated in Fig. 11, and as soon as the ratchet sleeve starts upwardly with the spindle for compressing the spring, the cam action between the shoe 51^a and inclined way 48^a will shift or rotate the ratchet sleeve, and with it the lower segment of the ratchet spindle about its axis, the distance occurring between two adjacent grooves or keyways 47, and as the upward motion of the ratchet sleeve continues as indicated in Fig. 12, the shoe will line up with the next groove in which it runs, thus stopping the rotary movement of the spindle, and confining it to a longitudinal reciprocatory movement, until the end of the next working stroke will have been reached, whereupon the same operation will be repeated. It will thus be seen that as the spindle is reciprocated it is intermittently rotated a part of a revolution. The spring pressed pawl 44 in coöperating with the ratchet wheel 41 will prevent any tendency for reverse rotation on the part of the spindle.

The lower end of the spindle or shaft is equipped with a socket 54, in which a plate 55, serrated at its lower portion as at 56, is carried. This plate is adapted to be clamped against the shank of a drill through the action of set screws 57 for securing the drill in place.

Although I have described the preferred embodiment of my invention, I may desire

to make such changes in the construction, combination and arrangement of parts thereof as do not depart from the spirit of the invention and the scope of the appended claims.

I claim:

1. In a drill, a spindle, longitudinally arranged key-ways on the spindle, said key-ways having intercommunicating inclined-ways near one end, means for imparting a reciprocatory movement to the spindle, and a trigger mounted to receive an oscillatory movement and prevented from moving longitudinally with the spindle and having a shoe to coöperate with the said key-ways and inclined-ways to impart a step by step rotary movement to the spindle.

2. In a drill, a reciprocating spindle provided with longitudinally disposed key-ways and intercommunicating inclined-ways, a trigger mounted to oscillate and prevented from moving longitudinally with the spindle and having a shoe to coöperate with the key-ways and inclined ways to impart a step by step rotary movement to the spindle, a ratchet wheel having splined connection with the said spindle to turn therewith but leaving such spindle free to reciprocate therein, and a pawl coacting with the ratchet wheel to prevent backward rotation thereof.

3. In a drilling machine, a reciprocating spindle, means for actuating the spindle, a ratchet sleeve fixed on the spindle, and having a plurality of spaced parallel grooves extending longitudinally of the sleeve, inclined ways extending in a common direction and interconnecting the grooves near the upper ends of the latter, a trigger relative to which the ratchet sleeve is adapted to reciprocate, said trigger including a shoe slidable in the grooves, spring means for directing the shoe into one of the inclined ways when the ratchet sleeve reaches one end of its stroke, a ratchet wheel slidably keyed upon the ratchet sleeve, and means coacting with the ratchet wheel in preventing reverse rotation of the ratchet sleeve.

4. A drilling machine including a reciprocating spindle, a ratchet sleeve fixed thereon and provided with a series of spaced parallel grooves extending longitudinally of the sleeve, inclined parallel ways interconnecting the grooves adjacent one end of the latter, a shoe slidable in the grooves and in relation to which the sleeve is adapted to reciprocate, means for automatically directing the shoe into succeeding inclined ways, as the ratchet sleeve reaches the end of its stroke in one direction, a ratchet wheel mounted on the sleeve, and means cooperating with the ratchet wheel in preventing reverse rotation of the ratchet sleeve.

5. In a drilling machine, a reciprocating spindle, a ratchet sleeve fixed thereon and

provided with a plurality of spaced parallel grooves extending longitudinally of the said sleeve, inclined parallel ways interconnecting the grooves adjacent one end of the latter, a shoe slidable in the grooves and in relation to which the sleeve is adapted to reciprocate, means for automatically directing the shoe into succeeding ways as the sleeve reaches the end of its stroke in one direction, and means for preventing reverse rotation of the ratchet sleeve.

6. A drilling machine including a casing, a reciprocating spindle extending thereinto, a ratchet sleeve fixed in relation to the spindle and arranged within the casing, said sleeve being provided with a plurality of longitudinally extending parallel grooves, inclined parallel ways interconnecting the grooves adjacent one end of the latter, means mounted on the casing slidably engaging in the grooves, means for automatically directing the first said means into the inclined ways as the ratchet sleeve reaches the end of its stroke in one direction for imparting an intermittent rotary movement to the ratchet sleeve, a ratchet wheel slidably keyed on the ratchet sleeve, and means carried by the casing co-operating with the ratchet wheel in preventing reverse rotation of the ratchet sleeve.

7. A drilling machine, comprising a cas-

ing, a spindle mounted within the casing and adapted to have a reciprocating movement imparted thereto and provided with longitudinal key-ways and intercommunicating ways, a trigger mounted upon the casing and having a shoe to coact with the longitudinal key-ways and the inclined-ways to impart a step by step rotation to the spindle, a ratchet wheel mounted within the casing and having the spindle slidable therein and rotatable therewith, and a pawl carried by the casing and co-operating with the ratchet wheel to prevent backward rotation thereof and the spindle.

8. In a drilling machine, a reciprocating spindle, a ratchet sleeve fixed thereon and provided with a plurality of parallel grooves, inclined grooves interconnecting the parallel grooves, means with respect to which the sleeve reciprocates for traveling in the grooves, and means for automatically causing the travel of the first said means through successive inclined grooves as the sleeve reaches the end of its stroke in one direction for intermittently causing the rotation of the sleeve, and means for preventing reverse rotation of the ratchet sleeve.
